SWITCH MECHANISM

Vincent G. Apple, Dayton, Ohio, assignor to
 Bendix Brake Company, South Bend, Ind., a
 corporation of Illinois

Application January 23, 1930. Serial No. 422,747

4 Claims. (Cl. 200—83)

My invention relates to electric switches and has particular reference to that type of switch wherein the member which bridges the contacts is controlled by the movement of a pressure diaphragm.

5 An object of my invention is to provide a pressure diaphragm switch which may be utilized to control the circuit which drives an air compressor. I contemplate utilizing the air compressor for some such purpose as maintaining adequate pressure in a compression tank for operating brake mechanism on an automotive vehicle.

10 A particular object of my invention is to so design this pressure operated switch that it will permit the pressure bearing against the diaphragm member thereof to vary within a certain predetermined range without functioning to close the switch and so start the compressor.

15 Still a further object of my invention is to provide a very simple, compact, and efficient switch of high current carrying capacity which may be easily mounted on any electrical or automotive apparatus.

20 Still other objects and meritorious features will become apparent from the following description taken in conjunction with the drawings wherein like numerals refer to like parts throughout the several figures and wherein:

25 Fig. 1 is a sectional elevation of my improved mechanism,

Fig. 2 is a similar view wherein the switch is in open position,

30 Fig. 3 is a plan view of the reinforcing plate utilized in conjunction with my pressure diaphragm,

Fig. 4 is a section on the line 4—4 of Fig. 1,

Fig. 5 is a plan view of my switch member,

Fig. 6 is a fragmentary view, partly in section, 35 illustrating the manner in which my switch casing is held together, and

Fig. 7 is a detailed view of one of the side rocker arm members utilized to actuate the switch bridge member.

40 Numeral 10 indicates the supporting base for my switch assembly. It is provided with apertures 12 for the purpose of securing it to any convenient support. At one side thereof there is a conduit 14 which is for the purpose of connecting the pressure chamber 16, formed in the base, with some reserve supply of pressure such as a pressure tank. Seated on the base member 10 and stretched across the chamber 16 is the diaphragm 18. This diaphragm is secured in place 45 by means of plate 20 which functions as a clamp-

ing means therefor, and also provides an annular seat for the ring 22, which latter acts in conjunction with the plate 20 to insure the proper degree of tautness in the diaphragm membrane. A second plate member 24, which is composed of 60 any desirable flexible material, preferably fabricated, is seated on the diaphragm 18 and secured in that position by means of the ring 22. This second plate member 24 is provided with a central aperture whereby it is secured to the plunger 65 26. The plate 20 is provided with a central aperture through which the plunger 26 extends, and this plunger is provided with a plate 28 at its upper extremity which serves as a bearing for the inner ends of the rocker arms 30. A plurality of 70 studs 32 are secured to the underside of the plate member 20 and these stud members serve as supports for pivoting the said rocker members 30. Each of the stud members 32 is provided with an upwardly extending flange 34 on the outer side 75 of its upper extremity, and these flanges form a positive seat for the plate member 36. The coil spring 38 is seated on this plate member 36 and its upper extremity bears against another plate member 40, which is cup shaped as indicated in 80 Figs. 1 and 2, so that it may seat within the upper end of the coil spring 38.

85 A casing 42 is seated upon a peripheral flange on the plate 20 and bolts 44 are threaded through the base, plate member 20, and upper portion of the casing for the purpose of retaining the various units together. Secured to the upper portion of the casing in the form of a unit, held together and insulated from one another by the spaced assembly generally indicated by 46, are the two contact members 48. An aperture is provided in the top of the casing 42 through which extends a plunger 50. This plunger is seated in a central aperture in the cup of plate 40, and provided with a flange at its lowermost extremity for the purpose of seating a spring 52. At its upper extremity this spring 52 bears against the underside of casing 42. Secured to the upper end of the plunger 50 is the bridge 54.

90 As clearly illustrated in Figs. 1 and 2 each of the rocker members 30 is pivoted at its central point and provided on its inner end with a roller member 56. Each rocker member 30 is pivoted at its central point and provided on its outer extremity with a camming slot 58 into which a 95 pin on the lower extremity of link 60 is inserted. The upper end of each of these links is pivoted to the periphery of plate 40.

95 The operation of my pressure switch will be obvious from the foregoing description, but will 100 105 110

be briefly outlined herein. The spring members 38 and 52 are so balanced that the resultant of their pressure will normally retain the bridge member 54 in contact with the contact members 48, and thus close the electric circuit. This position of the members is illustrated in Fig. 1 of the drawings. When the pressure in the pressure chamber 16 has reached a predetermined minimum, as illustrated by the showing of Fig. 1, the resultant of the pressures of the springs will have closed the contacts, started an electric circuit through the compressor member, and thus starting the building up of maximum pressure in the storage tank. As soon as this maximum pressure in the storage tank has been obtained, it will be transferred to the pressure chamber 16 of the switch, thus raising the diaphragm member 18. The plunger 26 which is constrained to move in accordance with the diaphragm member 20 will raise the plate 28 and thus raise the inner end of the rocker member 30. This movement of the rocker member 30 will cause a corresponding downward movement of the outer ends of the rocker member, thus drawing down the bridge member 54, utilizing the combined pressure exerted against the diaphragm 18 and the advantageous camming surface of the slot 58 bearing against the pin of link 60.

This movement of the link 60 draws the plate member 40 down with it against the resultant pressure of the springs 52 and 38, thus opening the circuit.

It is thus apparent that not until the pressure in the pressure chamber 16 has reached a value below that of the resultant pressure of the two springs 38 and 52 will these springs be able to force the bridge member 54 upwardly to form a contact with the contact members 48 and thus close the circuit to operate the compressor. This provides a definite, predetermined range of pressures within which the switch will not close for the purpose of permitting the compressor to function. This will be the useful range of pressures within which the pressure in the storage tank is sufficient to carry out the purposes for which it was designed.

Furthermore, by simply shifting the relative position of the camming slot 58 in the outer end of the rocker arm 30, less pressure will be required to withdraw the bridge member 58 from the contact members 48 and in this way the particular range of useful operating pressures may be predetermined prior to assembling the switch. In other words, rocker members containing various shaped slots may be assembled with all

of the other standard parts, thus necessitating the manufacture in other than standard manner of but one part of this assembly.

Various modifications of my device will be apparent to those skilled in the art, and for that reason I intend to limit myself only within the scope of the appended claims.

I claim:—

1. An electric switch comprising a hollow body member having a central aperture in its top, a contact member including a flanged stem axially slidable through said aperture, a plate supporting the lower extremity of said stem, a coiled spring thereabout seated upon the flange of said stem and bearing against the underside of said top, a second spring supporting said plate, a pressure sensitive diaphragm, and operative connections between said plate and diaphragm.

2. Mechanism for expanding and compressing a coil spring in response to a force variation coaxial therewith comprising plates positioned against the opposite ends of said coil spring, one of said plates being free to move with one end of the spring and the other plate constituting a relatively fixed abutment for the other end of the spring, a rocker arm pivoted about a point fixed with reference to said abutment plate, a link connecting one end of the rocker arm and the movable plate, and a member movable coaxially with said spring in response to force exerted therein coupled with the opposite end of the rocker arm.

3. Mechanism of the described class comprising a fixed plate, a coil spring seated thereon, a plate floatingly supported upon the opposite end of said spring, a member movable axially with reference to said spring slidably positioned below said fixed plate, a rocker arm pivoted about a fixed point adjacent said axially movable member and having one arm engageable therewith, and a link connecting the other end of said rocker arm with the floatingly supported plate.

4. Switch mechanism of the class described comprising a casing, a coil spring therein, a plate arranged at each end of the spring, rocker mechanism operable to urge one of said plates to compress the spring, a link slidably coupled with said rocker mechanism and connected with the plate at the opposite end of the spring operable upon movement of said rocker mechanism against the first plate to compress the spring to simultaneously urge the other plate in the opposite direction against the tension of the spring, and a switch contact carried by said second plate.
